DOUBLE THROW SWITCH

Howard W. Graybill, Honey Brook, Pa., assignor
to Westinghouse Electric Corporation, East
Pittsburgh, Pa., a corporation of Pennsylvania

Application August 21, 1947, Serial No. 769,909

6 Claims. (Cl. 200—48)

1

This invention relates to double throw electric switches generally, and especially to high voltage disconnect switches of this type.

Switches of the disconnect type which are mounted outdoors often give trouble by reason of the switch operating mechanism becoming fouled as by ice, dirt or corrosion. Single throw switches designed to avoid these difficulties are known wherein the mechanism is completely enclosed as in H. L. Rawlins Patent No. 2,363,360, issued November 21, 1944, on Circuit interrupters, to the same assignee of this invention. Heretofore, however, the additional mechanism required for double throw switches, especially where such switches are of the high contact pressure type wherein the switch blade has a compound movement in different directions, has made it impossible to adequately protect the mechanisms of these switches.

Accordingly, one object of this invention is to provide novel operating mechanism for disconnect switch blades having compound movement and of the double throw type.

Another object of this invention is to provide a novel simplified actuating mechanism for double throw disconnect switches which is adequately protected from the atmosphere.

Another object of this invention is to provide a novel cam mechanism for double throw disconnect switches of the type described.

These and other objects of this invention will become more apparent upon consideration of the following detailed description of a preferred embodiment thereof, when taken in connection with the attached drawings, in which:

Figure 1 is a top plan view of a switch constructed in accordance with this invention;

Fig. 2 is an enlarged longitudinal section view taken substantially centrally through the supported end of the switch blade shown in Fig. 1.

Fig. 3 is an end view of the supported end of the switch blade with a part of the supporting housing broken away, and

Fig. 4 is a profile of the cam track employed in the switch shown in Figs. 1 to 3.

In the embodiment of this invention illustrated on the drawings, it will be seen from Fig. 1 that the switch is adapted to be supported on a base 2 which may be of channel form, with one stationary insulator 4 mounted at one end of base 2, and a second stationary insulator 6 mounted at the other end of base 2. A third stationary insulator 8 is adapted to be mounted at the outer end of a short base member 10 which extends laterally from base 2 substantially midway be-

2

tween insulators 4 and 6, and is secured to base 2 in any desired manner.

Insulator 4 has mounted on the outer end thereof a terminal plate 12, as by bolts 16, and this terminal plate supports contact jaws 14 which may be either integral with or formed separately from terminal plate 12 and secured thereto by a bolt 16. Similarly, insulator 6 has secured to the outer end thereof a terminal plate 18, as by bolts 22, and is provided with contact jaws 20 like the contact jaws 14.

Stationary insulator 8 has secured to the outer end thereof one end of a supporting bracket 24, as by bolts 26, with the outer end of the bracket 15 being formed to provide a flat terminal pad 28. The inner end of supporting bracket 24 extends to the outer end of a fourth insulator 30 adapted to be rotatably mounted at its other end in supporting base 2. The outer end of insulator 30 is provided with a cap 32 which may be secured thereto in any desired manner as by bolts 33, and this cap has secured to the projecting central portion thereof an actuating crank 34, as by screws 36. As illustrated in Fig. 2, the juncture 20 of cap 32 and crank 34 is located in the region of the inner end of supporting bracket 24, and is grooved to form with an opposed groove formed in an opening in this end of bracket 24, a raceway for ball bearings 38 so that the outer end of rotatable insulator 30 is rotatably supported by bracket 24 from stationary insulator 8.

The movable switch blade is adapted to be supported on bracket 24 in a manner to be described, and this blade comprises a tubular blade member 40 which is rotatably mounted substantially on its longitudinal axis in a bearing provided by an opening in one wall 44 of a supporting housing 42. Blade 40 at its supported end has a plug 46 secured therein, as by bolts 48, with the plug having a shoulder adapted to abut against the housing wall 44 to prevent withdrawal of the blade 40, and further having an integral fork 50 within housing 42, for a purpose to be described. Housing 42 may also have spaced integral extensions 45 52 extending in a direction along blade 40 and being joined at their outer ends by an integral bearing portion 54, which forms a second bearing for the supported end of blade 40 at a point spaced outwardly from wall 44 of housing 42. If desired, one housing extension 52 may have secured thereto as by bolts 58, a contact spring 56 resiliently engaging the outer surface of blade 40, to form a good conducting path from blade 40 to supporting housing 42. Blade supporting housing 42 is adapted to be

supported on bracket 24 by a pair of spaced lugs 60 and 62, which may be formed integral with housing 42, and are apertured for receiving pivot bolts 66 passing through the apertures in these lugs and through apertures provided in spaced supporting arms 64 secured on or integral with bracket 24.

At a point opposite wall 44 of housing 42, there is provided an opening 68 in the housing which is adjacent to and intersects the axis of pivotal movement of the blade and housing on pivot bolts 66. Opening 68 in housing 42 is adapted to receive a substantially spherical portion 70 of crank 34, with the crank further including an angularly extended crank portion 72 adapted to be disposed within housing 42. Crank portion 72 is provided to its outer end with a cam follower roller 74 mounted on crank portion 72 as by a screw 76. Cam roller 74 is adapted to travel in grooved cam tracks 78 and 80 cut into the inner surface of certain walls of housing 42.

Housing 42 also includes an integral actuating lug 82 adapted to be received in a notch 84 formed on crank 34 at one pivotal position of the switch blade and its housing relative to pivot axis 66. It will be noted that the outer end of blade 40 is provided with a flat tip 86 of a width slightly in excess of the spacing between the contact jaws 14 and 20, so that when blade tip 86 is located transversely of either pair of contact jaws it will be in high pressure contact engagement therewith. If desired, inserts 88 may be provided on opposite sides of blade tip 86 of an arc resistant material having good electrical conducting qualities, to form the actual contact of the blade with the contact jaw.

Fig. 4 illustrates in profile cam tracks 78 and 80, with the angle A indicating the angle at which each point on each cam track is located relative to the horizontal plane as viewed in Figs. 1, 2 and 3, with the switch in the closed position illustrated in these figures. The angle B of Fig. 4 indicates the angular rotation of insulator 30 required to position crank roller 74 at each point along the cam tracks. It will be observed from Figs. 3 and 4 that cam tracks 78 and 80 meet at one point which corresponds to a position of the blade relative to the axis of pivot bolts 66 substantially midway between insulators 4 and 6, or at an angle of about 90° from that shown in Figs. 1, 2 and 3.

In the operation of the switch described above and illustrated on the drawings, it will be observed that if it is desired to operate the switch from the closed circuit position shown in Figs. 1, 2 and 3 wherein it engages contact jaws 20, it is necessary to rotate insulator 30 in a counter-clockwise direction as viewed in Fig. 1. Initial opening movement of rotatable insulator 30 results in crank roller 74 travelling along a straight portion of cam track 78 for a distance corresponding to almost 20° rotation of the rotatable insulator. During this initial rotation of insulator 30, no pivotal movement of blade 40 occurs on the axis of pivot bolts 66 inasmuch as this initial portion of cam track 78 is horizontal. However, inasmuch as an intermediate portion of angular crank part 72 is received in fork 50 of the switch blade, the blade will be rotated during this initial movement of insulator 30 about the longitudinal axis of the blade to position the flat blade tip 86 at an inclination with respect to contact jaws 20, where the tip will no longer be in high pressure contact with the jaws. Upon continued rotation of insulator 30 in the same direction, 75

crank roller 74 enters the intermediate portion of cam track 78 to cause supporting housing 42 and blade 40 to move about pivot bolts 66 until an upright position of the blade is reached when crank roller 74 will have reached the intersection of cam trackways 78 and 80. At this medial position of the switch blade, crank roller 74 has a choice, upon continued rotation of insulator 30 in the same direction, of returning along trackway 78 or of entering trackway 80. In order that such continued rotation of insulator 30 in the same direction shall cause switch blade 40 to move into engagement with contact jaws 14, it is necessary that crank roller 74 enter trackway 80, and this is the purpose of projection 82 of the housing, for at such medial position the projection 82 will be received in notch 84 provided on crank 34. It will be apparent, accordingly, that continued rotation of insulator 30 in the same direction will cause blade housing 42 and the blade to be kicked over toward contact jaws 14 by projection 82, thus causing crank roller 74 to enter trackway 80. It will be apparent that after passing the medial position, crank roller 74 will continue along trackway 80 until it reaches the flat end thereof corresponding to a position of switch blade 42 where the blade tip 86 is received between contact jaws 14, but at an inclination thereto, whereupon continued travel of crank roller 74 along the flat end portion of trackway 80 causes rotation of blade 42 about its longitudinal axis to a position where blade tip 86 is positioned transversely of contact jaws 14 and into pressure engagement therewith. If it is desired to actuate switch blade 40 back into engagement with contact jaws 20, it is merely necessary to rotate insulator 30 in the opposite direction, whereupon the opposite of the movements described above will occur.

It is apparent from the description given above of one embodiment of this invention, that the invention includes the provision of a novel switch mechanism especially adapted for a switch of the type where a switch blade is mounted for rotation substantially about its axis into and out of high pressure engagement with line contacts, and is also mounted for pivotal movement toward and away from such contacts, which mechanism is adapted to actuate such a switch of the double throw type, while at all times it positively correlates the angular position of the flat blade tip relative to the longitudinal axis of the blade and with the angular position of the blade about its pivot axis on which it moves into and out of engagement with the line contacts. Moreover, this mechanism is of the type which is substantially entirely closed, and thus adequately protected from the atmosphere.

Having described a preferred embodiment in this invention in accordance with the patent statutes, it is desired that the invention be not limited to this particular structure, inasmuch as it will be apparent, particularly to persons skilled in the art, that many changes and modifications may be made in this structure without departing from the broad spirit and scope of this invention. Accordingly, it is desired that the invention be interpreted as broadly as possible and that it be limited only as required by the prior art.

I claim as my invention:

1. In a double throw switch, spaced line contacts, a switch blade mounted on a support intermediate said contacts for pivotal movement of the blade into and out of engagement with either of said contacts, rotatable operating means for

said blade located adjacent said blade support, cam track and follower means associated with said blade and operating means, respectively, said cam track means comprising similar displaced portions joined at a location which substantially corresponds to the medial position of said blade and being cooperable with said follower means for causing movement of said blade at each side of a medial position, respectively, and means separate from said cam means for switching said follower means to one or the other of said cam track portions dependent upon the direction of rotation of said operating means.

2. In a double throw switch, spaced line contacts, a switch blade having a housing portion at one end mounted on a support intermediate said contacts for pivotal movement of the blade into and out of engagement with either of said contacts, said housing portion having an opening adjacent the pivot axis of said blade, rotatable operating means for said blade located adjacent said blade support and extending into said housing portion through said opening, cam track and follower means associated with an inner wall of said housing portion and a part of said operating means within said portion, respectively, said cam track means comprising similar displaced portions joined at a location which substantially corresponds to the medial position of said blade and being cooperable with said follower means for causing movement of said blade at each side of a medial position, respectively, and means separate from said cam means but outside of said housing portion for switching said follower means to one or the other of said cam track portions dependent upon the direction of rotation of said operating means.

3. In a double throw switch, spaced line contacts, a switch blade mounted for rotation about a longitudinal axis on a support which in turn is mounted intermediate said contacts for pivotal movement of the blade into and out of engagement with either of said contacts, rotatable operating means for said blade located adjacent said blade support, cam track and follower means associated with said support and operating means, respectively, said cam track means comprising similar displaced portions joined at a location which substantially corresponds to the medial position of said blade and being cooperable with said follower means for causing movement of said blade at each side of a medial position, respectively, and means separate from said cam means directly connecting said blade and operating means for rotating said blade about said longitudinal axis upon operation of said operating means in predetermined relation to pivotal movement thereof.

4. In a double throw switch, spaced line contacts, a switch blade mounted for rotation about a longitudinal axis in a housing which in turn is pivotally mounted on a support intermediate said contacts for pivotal movement of the blade into and out of engagement with either of said contacts, said housing having an opening adjacent the pivot axis of said blade, rotatable operating means for said blade located adjacent said blade support and extending into said housing through said opening, cam track and follower

means associated with an inner wall of said housing and a part of said operating means within said housing, respectively, said cam track means comprising similar displaced portions joined at a location which substantially corresponds to the medial position of said blade and being cooperable with said follower means for causing movement of said blade at each side of a medial position, respectively, and means separate from said cam means directly connecting said blade and operating means for rotating said blade about said longitudinal axis upon operation of said operating means in predetermined relation to pivotal movement thereof.

5. In a double throw switch, spaced line contacts, a switch blade mounted on a support intermediate said contacts for pivotal movement of the blade into and out of engagement with either of said contacts, rotatable operating means for said blade located adjacent said blade support, cam track and follower means associated with said blade and operating means, respectively, said cam track means comprising similar displaced portions joined at a location which substantially corresponds to the medial position of said blade and being cooperable with said follower means for causing movement of said blade at each side of a medial position, respectively, and means separate from said cam means for switching said follower means to one or the other of said cam track portions dependent upon the direction of rotation of said operating means, comprising parts associated with said blade and operating means, respectively, which are positioned to intermesh at said medial position of said blade.

6. In a double throw switch, spaced line contacts, a switch blade mounted for rotation about a longitudinal axis in a housing which in turn is pivotally mounted on a support intermediate said contacts for pivotal movement of the blade into and out of engagement with either of said contacts, said housing having an opening adjacent the pivot axis of said blade, rotatable operating means for said blade located adjacent said blade support and extending into said housing through said opening, cam track and follower means associated with an inner wall of said housing and a part of said operating means within said housing, respectively, said cam track means comprising similar displaced portions joined at a location which substantially corresponds to the medial position of said blade and being cooperable with said follower means for causing movement of said blade at each side of a medial position, respectively, means separate from said cam means directly connecting said blade and operating means for rotating said blade about said longitudinal axis upon operation of said operating means in predetermined relation to pivotal movement thereof, and means separate from said cam means and located exteriorly of said housing for switching said follower means to one or the other of said cam track portions dependent upon the direction of rotation of said operating means.

HOWARD W. GRAYBILL.
